UNITED STATES PATENT OFFICE.

WILLIAM M. BECK, OF ELWOOD, INDIANA, ASSIGNOR OF ONE-THIRD TO
CHARLES T. PARKER, OF FAIRMOUNT, INDIANA.

MEANS FOR SIGNALING AND STOPPING RAILWAY-VEHICLES.

No. 852,156.

Specification of Letters Patent.

Patented April 30, 1907.

Application filed December 14, 1905. Serial No. 291,688.

To all whom it may concern:

Be it known that I, WILLIAM M. BECK, of Elwood, county of Madison, and State of Indiana, have invented a certain new and useful Means for Signaling and Stopping Railway-Vehicles; and I do hereby declare that the following is a full, clear, and exact description thereof, reference being had to the accompanying drawings, in which like letters refer to like parts.

One object of this invention is to prevent wrecks on railways due to open switches. This object is accomplished by providing means in the track connected with and actuated by the switch for operating means mounted on the locomotive, car or vehicle for giving a signal, shutting off the power, and throwing the brakes into operation. The purpose is to provide mechanical means for automatically doing this work so that dependence will not have to be placed upon the engineer or driver for preventing a wreck by an open switch.

Another feature consists in providing means in the railway for operating the whistle on the locomotive or signal on the car for any purpose.

The nature of this invention will be understood from the accompanying drawings and the following description and claims.

In the drawings Figure 1 is a side elevation of a portion of a railway and a large locomotive thereon, shown largely in dotted lines, the same being equipped with my said invention. Fig. 2 is a central vertical section of the valve mechanism connected with the air pipe of the brake system; and a side elevation of the means for operating the same, parts being broken away and parts shown in dotted lines. Fig. 3 is a central vertical section of the cylinder connected with the air pipe for operating the throttle of the locomotive, parts being broken away. Fig. 4 is a perspective view of the means mounted in the railway for actuating the parts on the locomotive. Fig. 5 is a side elevation of said means as mounted, the upper or actuating position being shown by dotted lines. Fig. 6 is a plan view of a section of the railway, showing switches equipped with my improved means for operating parts of a locomotive, car or other vehicle. Fig. 7 is a vertical transverse section on the line

7—7 of Fig. 6, the switch being shown closed. Fig. 8 is the same with the switch open. Fig. 9 is a section on the line 9—9 of Fig. 6, an altered position of the switch rail being shown by dotted lines. Fig. 10 is a perspective view of a portion of the railway and means for actuating the parts of the locomotive and the mounting for said means, and engaging parts on the locomotive in position, parts being in vertical section.

In detail 10 represents a portion of a locomotive, 11 is the whistle, and 12 a lever for actuating the whistle, the lever being fulcrumed at 13. A bracket 14 is secured to the boiler at 15. The lever 12 is actuated by a wire 16 which at its lower end is attached to the bell-crank lever 17 fulcrumed at 18 to the side of the locomotive. The downwardly extending arm of said bell-crank 17 projects horizontally and transversely of the track so as to be engaged by the upward projection 19 from the track-plate 20 when the latter is elevated, as shown by dotted lines in Fig. 5. When the means just described draws the wire 16 downward it operates the whistle. This arrangement may be employed for a danger signal in advance of switches or railway crossings, or as a crossing signal for use in advance of highway crossings.

To the rear of the whistle-actuating mechanism 17, means is provided for stopping the locomotive or train. To that end a lever 21 is fulcrumed at 22 to the valve casing 23 or other means secured to the locomotive or car in position under the lever 21 to engage the track plate 20. The lever 21 is curved so that it will ride up on the inclined upper surface of the plate 20 and be actuated thereby from the full line position shown in Fig. 2 to the dotted line position. The lever 21 is held in its actuated position by a rod 25 extending up through a slot in the plate 26 that has a sharp pawl-like point 27 which engages teeth or ratchets 28, the rod 25 being pressed toward said point 27 by a spring 29. This rod 25 projects upward with the handle 30 beside the cab of the locomotive, where it will be convenient for the engineer to reach and release it.

The lever 21 when actuated, as explained, will depress a valve 31 in the casing 23, from the full line position to the dotted line posi-

tion in Fig. 2 through the agency of the valve stem 32. Then air from the train line or air brake pipe 33 will rush through pipe 34 into the chamber of the valve casing 23 and through the pipe 35 to the cylinder 36, seen in Figs. 1 and 3, and there will actuate the piston 37 and rod 38 that has a slot 39 in which the throttle lever 40 extends and force the latter forward to close the throttle. As soon as the piston 37 in such movement passes the exhaust 41, the air will escape from the train line or air brake pipe 33, and thereby the air brakes will be immediately set after the throttle valve has been closed. This will immediately and automatically bring the locomotive and train to a stop.

After the engineer has released the rod 25 and lever 21, the spring 42 on the upper end of the rod 32 will depress said rod and the valve 31, whereupon the parts will resume their normal position. To neutralize the pressure on the piston, when valve 31 is closed a port 43 is provided in the chamber of the valve casing 23, which is closed by the valve 31 when in its downward position and opened by said valve when in its upper position. The slot 39 in piston rod 38 permits the engineer to freely operate his throttle.

While I have shown a specific means with a locomotive for operating the throttle lever and setting the air brakes, I do not wish to be limited to the details of said construction, nor do I wish the invention limited to the throwing of the throttle lever, for the device may be used in connection with electric motors or other motive power, or cars where the mechanism will operate a controller to throw the current off or device to stop the power or to operate the brakes.

The track plate 20 is substantially horizontal and extends longitudinally of the track and is inclined upwardly toward the middle from each end so that the parts of the locomotive or other vehicle to be engaged by it will be gradually affected during high speed and not be broken off. It has a vertical plate 19 to render the plate 20 rigid, and also to blow the whistle, and has downwardly extending arms 44 whereby it is fulcrumed upon the crank-shafts 45 mounted transversely of the railway, as shown in Fig. 10. These crank-shafts have at one side of the track rails 46 upwardly extending cranks 47 to which a wire or rod 48 is pivoted. This wire or rod 48 runs to the switch and is operatively connected therewith. This part of the construction as here shown, consists of a stand 49 mounted on a cross-tie 50 beside the track upon which a horizontal bell-crank 51 is fulcrumed. One arm of said bell-crank is pivoted on said wire or rod 48, and the other arm to the rod 52 that extends transversely through the track-rails 46 and the switch rail 53. A nut 54 is secured on

the transverse rod 52 in such position that the switch rail 53 when moved by the switch lever 55 against the rail 46 will operate the mechanism heretofore described and elevate the plate 20 to the dotted line position shown in Fig. 5. Consequently the switch being open and in a dangerous condition, an approaching train will be automatically warned and stopped. This construction will not prevent the switch rail being moved from the rail 46 by the switch lever 56 as the nut 54 is only at the outside of the switch rail. When the switch is closed to the position shown in Fig. 6, the plate 20 at a distance will be moved downward by strong springs 58 to the full line position shown in Fig. 5, where it will not engage any part of the train.

With the arrangement described, the same wire or rod 48 may be connected with a plurality of switches. Thus in Fig. 6, the same wire or rod that runs to the first switch already described extends back to a second switch 57, turning off in an opposite direction. The parts there are the same as in the first mentioned switch, excepting the nut 54 is at the opposite side of the switch rail that is to be moved. The operation of these various switches will not interfere with each other, as the last mentioned switch can be opened without opening the first mentioned switch.

What I claim as my invention and desire to secure by Letters Patent is:

1. The combination with a railway, a locomotive movable thereon, a throttle lever on said locomotive, of a cylinder on a locomotive, a piston therein, a piston-rod with its outer end provided with a longitudinal slot through which said throttle lever extends so that said piston-rod may draw the lever in one direction and leave the lever free to be operated by the engineer when the piston-rod is idle, an exhaust at one end of the cylinder, a pipe entering the cylinder from a supply of fluid under pressure, means for regulating the admission of said fluid to said cylinder, and means in the railway track for causing the operation of said regulating means.

2. The combination with a railway, of means in the railway track for actuating parts of a vehicle passing on the track, a switch with a movable switch-rail recessed on the side next to the main rail, means for throwing said switch-rail, a rod passing loosely through said switch and main rail with a stop-nut thereon registering with the recess in the switch-rail, a bell-crank mounted in the track with one arm pivoted to said rod and a connection between the other arm of said bell-crank and the means in the track for operating the parts of the vehicle.

3. The combination with a railway, of a plate extending longitudinally of the railway and adapted when elevated to engage parts

of a vehicle traveling on said railway, a pair of crank-rods mounted transversely in the rails with said plate mounted on the cranks thereof, a switch provided with a switch-rail, and means actuated thereby for oscillating said crank-rods.

5 In witness whereof, I have hereunto affixed

my signature in the presence of the witnesses herein named.

WILLIAM M. BECK.
